COMBINED SALT AND PEPPER SHAKER

James A. Sewell, 4437 Providence St.,
Houston, Tex. 77020

Filed June 13, 1972, Ser. No. 262,225

Term of patent 14 years

Int. Cl. D7—06

U.S. Cl. D7—57

FIG. 1 is a perspective view of the combined salt and pepper shaker; and

FIG. 2 is a side view of the combined salt and pepper shaker of FIG. 1; and

FIG. 3 is a top view of the combined salt and pepper shaker of FIG. 1; and

FIG. 4 is a bottom view of the combined salt and pepper shaker of FIG. 1.

I claim:

The ornamental design for a combined salt and pepper shaker, substantially as shown.
